UNITED STATES PATENT OFFICE

2,415,902

LAMP BASE AND HOLDER

Edward B. Noel, Cleveland Heights, Ohio, assignor
to General Electric Company, a corporation of
New York

Application April 12, 1944, Serial No. 530,667

15 Claims. (Cl. 176—32)

1

My invention relates to lamps having electric current inleads engaging with a base and is concerned with the base construction as well as with holding means for engaging with said base. My invention is particularly advantageous for photoflash lamps, that is, lamps comprising combustible material, a supporter of combustion and electric ignition means disposed in an electromagnetic radiation transmitting bulb. Such lamps emit actinic light useful for photographic purposes.

Photoflash lamps comprising a base which forms part of the lamp bulb or envelope wall and which is secured and sealed to the neck of the bulb or envelope by an organic plastic are disclosed in copending application Serial No. 461,578, filed October 10, 1942, by John W. Fulton and Alton G. Foote, which application is assigned to the assignee of this application. One species of base disclosed in the copending application consists of an electrically insulating organic plastic, has a perforated disc-like bottom web through which the current inleads pass and a cylindrical rim integral with the peripheral portion of the web. The portion of the inleads external to the base constitute electrical contacts.

An object of my invention is to provide a base structure of the above type which is engageable with diverse types of holding and connecting means, or sockets for said base. Another object of my invention is to provide such a base structure which may be indexed in predetermined position in a holding means. A further object of my invention is to provide means for holding my new base. Further objects and advantages of my invention will appear from the accompanying drawings and the appended claims.

In the drawings, Fig. 1 is a side view of a photoflash lamp provided with a base embodying my invention; Fig. 2 is a top plan view of the base shown in Fig. 1; Fig. 3 is a front view of the base illustrated in Figs. 1 and 2; Fig. 4 is a front elevational, fragmentary, partly sectional view of a socket in which my new base is insertable; Fig. 5 is a perspective, fragmentary view of another socket; Fig. 6 is a side elevational view of a modified type of socket shown in Fig. 5; Fig. 7 is a similar view of another modified type of socket similar to that shown in Fig. 5; Fig. 8 is a top plan view of the base and spring holding member of the socket shown in Fig. 7; Fig. 9 is a fragmentary perspective view of a holder for a plurality of my new lamp bases; Fig. 10 is a sectional view along the line 10—10 of Fig. 9 and showing in full a base in the holder; Fig. 11 is a fragmentary, perspective view, as seen from above,

2

of another species of holder; Fig. 12 is a similar view, as seen from below, of the holder shown in Fig. 11, and Fig. 13 is a sectional view along the line 13—13 of Fig. 12 and showing in full a lamp base in the holder; Fig. 14 is a side elevational view of another base embodying my invention and insertable in the holders shown in Figs. 4, 9 and 10; Fig. 15 is a top plan view of the base shown in Fig. 14 and Fig. 16 is a similar view of another species of base of my invention insertable in the holders shown in Figs. 4 to 10.

Referring to Fig. 1 of the drawings, the photoflash lamp 20 comprises a light transmitting bulb 21 having a short cylindrical neck 22 extending into and terminating in the cavity of a base 23. The base 23 acts as a cap for the bulb 21 to constitute part of the bulb wall and support a pair of current inlead wires 24 and 25 which pass through perforations or apertures 26 and 27, respectively, in the base. Two other apertures 28 and 29 are provided in the web of the base for the end portion of each of the inleads 24 and 25, respectively. The inleads 24 and 25 pass through said apertures 26 and 27 to the outside of the base and terminate in the other of said apertures 28 and 29 to prevent rotation of said inleads in said base. The exposed portions 30 and 31 of the inleads 24 and 25, respectively, serve as contact terminals for engagement with the contacts of an electrical circuit including a source of electrical energy suitable for igniting the photoflash lamp 20.

The current inleads 24 and 25 terminate within the bulb 21 in portions 32 and 33, respectively, of reduced diameter which portions are bridged by a filament 34 which, when energized, ignites the combustible material deposited in the form of beads 35 on the end portions of the inleads. The bulb 21 preferably contains an oxidizing gas at atmospheric pressure, or lower. The bulb 21 is made gas tight by an electrically insulating, organic plastic 36 which adheres to the bulb neck 22, the inleads 24 and 25 and the base 23 which are thus secured together with the joints between them gas-tight as disclosed in the Fulton and Foote application referred to above.

As shown in Figs. 1 to 3, the base 23 comprises a bottom or web portion 37 having a comparatively thick circular central portion 38 which is slightly smaller in diameter than the inner diameter of the bulb neck 22. A rim portion 39 (Fig. 2) is integral with the base web 37 and has an inner cylindrical surface 40 spaced from the periphery of the central portion 38 and of slightly larger diameter than the outer diameter of the

bulb neck 22. An annular groove or recess 41 for accommodating the end of the bulb neck is thus provided between the central portion 38 of the base web 37 and the inner cylindrical surface 40 of the base rim 39. As shown in Fig. 2, the apertures 26 to 29 are aligned along a diameter of the central portion 38 of the base web 37 with one aperture 28 in the center of said portion 38 and another aperture 29 in the groove 41. The contact portions 30 and 31 of the inleads 24 and 25 are thus eccentrically disposed on the base 23 with contact 31 more eccentric than contact 30, as shown in Fig. 1.

The outer surface of the base rim 39 adjacent the base web 37 is square in transverse section and has rounded corners 42 (Fig. 3). This configuration of said surface makes possible the indexing of the base 23 by utilizing the parallel, planar, longitudinally extending surfaces thereof to properly orient the contacts 30 and 31 with the electrical contacts of suitable sockets described below. The part of rim 39 about the mouth of the base cavity has a pair of arcuate, diametrically disposed, support engaging flanges 43 projecting in opposite directions from the base 23 in a common plane including the mouth of the lamp accommodating cavity and normal to the longitudinal axis of said cavity of the base 23. The apertures 26 to 29 are in a plane connecting the most widely separated points on the arcuate edges of flanges 43. The flanges 43 are of sufficient thickness to be rigid and strong enough to withstand the forces exerted thereon by spring socket members or the like. As best shown in Fig. 2 the top surface of the base 23 has two parallel sides joined by curving ends of the flanges 43. The curved ends of the flanges 43 each extend through an angular distance of approximately 104 degrees measured from the center of the base web 37 to the respective ends of each of the 40 curved flanges.

A base 23 having the configuration described above and shown in the drawings is useful in conjunction with different types of sockets one of which is shown in Fig. 4 of the drawings. Referring to Fig. 4, the socket comprises a group of resiliently separable fingers 44 annularly arranged for embracing and gripping the flanges 43 of the base, and resiliently yielding contacts 45 and 46 surrounded by the fingers 44 for bearing against the contact portions 30 and 31 of the inleads 24 and 25, respectively. As shown, the free end portion of each of the fingers 44 are beveled to form surfaces one of which slopes upward and the other of which slopes downward from a ridge 47 formed at the juncture of the surfaces. The upwardly sloping surfaces of the fingers 44 engage the curved flanges of the base as it is inserted into the sockets so that the fingers 44 are spread outward as the base is thrust into the open mouth of the socket. As the flanges 43 are moved past the ridges 47 the downwardly sloping surfaces engage the base flanges 43 so that the force exerted in the direction of the socket center by the resilient, spread fingers 44 tends to retain the base 23 in the socket with the contact portions 30 and 31 bearing against the base contacts 45 and 46, respectively. The contact 46 is a ring formed by the end convolution of a helical, metal wire spring mounted on the reduced end 48 of the electrically insulative part 49 of the socket. The portion of part 49 adjacent its end 48 is surrounded and gripped by a solid walled shell 50 integral with the spring fingers 44. The ring contact 46 is of such radius

5 that it engages only with the more eccentric base contact 31 in any angular position of the base 23 in the socket. The contact 45 is in the form of the head of a pin having a shank 51 extending through the insulative body 49. The contact 45 is urged toward the mouth of the socket by a spring 52 bearing against the contact 45 and the bottom of a central bore 53 in the insulative part 49. The contact 45 is of such size that it engages the more centrally disposed base contact 30 in all possible angular positions of the base 23 in the socket.

10 The contacts 45 and 46 are provided with current inleads 54 and 55, respectively, which may be included in an electrical circuit comprising a conventional source of electrical energy, such as a conventional flashlight battery, suitable for igniting the photoflash lamp. A manually or automatically controlled switch of conventional type may be included in such circuit.

15 Another type of socket with which my new lamp base may be used is shown in Fig. 5 and comprises an electrically insulating plate 56 having an aperture 57 of the same configuration but of slightly larger dimensions than the flanged portion of the base 23 so that said portion may be passed through said aperture 57 with its largest dimension in the same direction as the largest dimension of the aperture 57. After the base 23 has been passed through the aperture 57 it may be rotated approximately 90 degrees to bring the flanges 43 of the base 23 into overlapping position with respect to the portions of the plate 56 adjacent the straight parallel sides of the aperture 57. The socket also comprises a pair of spaced, leaf-spring contacts 58 and 59 secured to plate 56. The contacts 58 and 59 engage with the base contacts 30 and 31 and urge the base 23 toward the plate 56 so that the flanges 43 bear against the plate surface portion which they overlap. Thus, the lamp base 23 is retained in the socket by the clamping action exerted in a direction parallel to the longitudinal axis of the base 23. If plate 56 is of metal, one of the contacts 45 20 or 59 is electrically insulated therefrom.

25 The free end portions of the contacts 58 and 59 have aligned grooves 60 and 61, respectively, which engage with the aligned contacts 30 and 31 of the base 23 to resist any tendency of the base 23 to rotate in the socket. The portions of the contacts 58 and 59 between the grooves 60 and 61 and the free end thereof slope away from the plate 56 so that the contacts may slide into the grooves easily as the base is rotated. 30 A stop 62 may be provided on the contact 59 by punching up a projection adjacent the groove 60 as shown in Fig. 5. The leaf spring contacts 58 or 59 may be made double as shown in Fig. 6 with one leaf 63 disposed between the contact 59 and the plate 56 and having a square end terminating adjacent the groove 61 to engage base contact 31 and thus to serve as a positive stop for the base 23.

35 The above described sockets retain the lamp base 23 by engaging with the contact terminals 30 and 31 and the base flanges 43. In Figs. 7 and 8 is shown a socket which retains the base 23 by engaging with the straight sided portions of the base so that the base 23 may be thrust therein and retained without the need for rotation. The socket comprises an insulating body 64 which has an aperture similar in shape and size to that shown in Fig. 5 and spring contacts 65 and 66 which are in the form of straight strips 40 without the grooves and bevelled portions of the

contacts 58 and 59 of Fig. 5 are bolted to the body 64. The contacts 65 and 66 are disposed transverse to the largest diameter of the aperture. A pair of straight wire spring members 67 and 68 are disposed in slots 69 and 70, respectively, in the opposed surfaces of the body 64 constituting the straight sides of the aperture. The wires 67 and 68 are held in cavities 71 in the body 64 partially in and partially out of the slots 69 and 70 so that when the base 23 is thrust into the socket the wires are pushed back into the slots 69 and 70, as indicated in broken lines in Fig. 8, to allow the base 23 to pass. After the base has passed the wires 67 and 68 spring back to their original position to engage the straight edges of the slot and the base (Fig. 7) as the latter is urged by contacts 65 and 66 toward the mouth of the aperture. Thus, the base 23 is retained in the socket. The base 23 may be removed by pressing it downward, tilting it slightly to pass by one wire 67 and 68 and then tilting it in the reverse direction to pass the other wire.

The outer surface portion of the base 23 between the web 37 and the flanged portion and which is square in transverse section is useful for indexing the base in proper position in a holder for a plurality of lamps, such as that shown in Figs. 9 and 10. The holder shown in these figures comprises a spring strip 72 of metal having its longitudinal edge portions 73 and 74 bent back so as to be parallel with the center portion 75 of the strip with the said edges 73 and 74 spaced sufficiently to form a slot which accommodates the square portion of the base 23 as shown in Fig. 10. The central portion 75 of the strip 72 has a plurality of aligned keyhole slots 76 having a straight sided opening 77 aligned with the slot between edges 73 and 74 and an elongated aperture 78 transverse to the length of the strip 75. The aperture 78 is of such size and shape as to permit passage of the base 23 therethrough. When the base 23 is inserted into said aperture 78 the square portion of the base 23 enters the slot defined by said edges 73 and 74 and the flanges 43 of the base 23 rest on the inner surface of the edge portions 73 and 74. The portions of the strip 72 adjacent the opening 77 having straight edges are shaped so as to form a cavity or depression to accommodate the base flanges 43, as shown in Fig. 10. The strip 72 is sufficiently elastic, resilient or springy so that the flanges 43 of the base 23 may be manually pressed against the edge portions 73 and 74 to separate these from the center portion 75 of the strip 72 a sufficient distance to permit moving the base 23 longitudinally of the strip 72 until the base flanges 43 are in position to engage the surfaces defining the cavity adjacent the edges of opening 77. The strip 72 flexes back to its original position, when manual pressure on base 23 is removed, to hold the flanges 43 against the surface of the cavity. Longitudinal relative displacement between the strip 72 and the base 23 is thus resisted, but the base 23 is removable from strip 72. Relative rotary displacement between the strip 72 and the lamp base 23 is positively prevented by the edges 73 and 74 of the strip engaging with the square portion of the base 23. Thus, the base contacts 30 and 31 are indexed properly in the strip 72 and are retained firmly therein for engagement with energizing contacts which may be aligned with the slot between the lower edge portions 73 and 74 of the strip 72.

After the lamps 20 have been flashed they are

readily removable from the strip 72 by the same method, that is, by first causing the edge portions 73 and 74 to flex and then moving the base 23 into aperture 78. Unflashed lamps may then be mounted in the holder or strip 72 in the manner described above.

The holder illustrated in Figs. 11 to 13 of the drawings is similar to that shown in Figs. 9 and 10 except that an elongated aperture 79 similar in shape to the top of base 23 extends longitudinally of a strip 80 and the edge portions 81 and 82 of the strip 80 has a square depression 83 (Fig. 12) approximately the size of the square portion of base 23. The sides of the depression 83 engage the lower straight edges of the base 23 to prevent relative longitudinal and rotary displacements between the base 23 and the strip 80. The lamp 20 is mounted on the strip 80 by inserting the base 23 through the aperture 79, forcing the base 23 against the lower edge portions 81 and 82 to separate said portions sufficiently to permit rotation of the base 23 so as to move the base flanges 43 under the portions of the strip 80 adjacent the straight edges of the aperture 79 as shown in Fig. 13. The edge portions 81 and 82 may be slit transversely, as shown at 84, on either side of the depressions 83 to facilitate insertion of base 23 by reducing the resistance to rotation of said base 23. The base 23 is retained in the strip 80 with the contact terminals 30 and 31 in proper position for engagement with contacts of an energizing circuit as said base terminals are moved into and out of engagement with the circuit contacts. The lamp 20 is readily removable from the holder or strip 80 by rotating the base 23 to index the flanges 43 with the aperture 79 and lifting the lamp 20.

The holders described above may be used in conjunction with apparatus for igniting the lamp simultaneously or in sequence. Such apparatus may be arranged to provide a multiplicity of flashes in rapid sequence to enable a photographer to take a series of pictures in a short time without handling each photoflash lamp individually. The holder carrying a plurality of lamps avoids such individual handling of lamps after they have been inserted in the holder.

The base illustrated in Figs. 14 and 15 of the drawing is similar to that illustrated in Figs. 1 to 3 except that the holder engaging flanges 43' are coplanar with the outer surface of the base web 37 and the square base portion is disposed between said flanges 43' and the mouth of the base cavity.

The base illustrated in Fig. 16 is similar to that shown in Figs. 14 and 15 except that the flanges 43' are circular arcs, the bottom of the base is circular and the top of the base about the cavity mouth has but two straight parallel, planar surfaces for indexing purposes.

The base described above and shown in the drawings, since they may be indexed into predetermined position in a holder, are advantageous for facilitating the insertion of the current leads therein in the high speed manufacture of lamps for which they are used.

In my copending application Serial No. 530,666, filed April 12, 1944, I have disclosed and claimed a lamp holder similar to those shown in Figs. 9 to 13 of this application and described and shown an apparatus for accommodating the lamp holders. The lamp holder of my application Serial No. 530,666 accommodates the lamp base disclosed in the Fulton and Foote application Serial No. 461,578 referred to above.

In my copending application Serial No. 530,668, filed April 12, 1944, I have described and claimed a multiple flash lamp device accommodating the lamps and lamp holders of this application and those of my application Serial No. 530,666.

What I claim as new and desire to secure by Letters Patent of the United States is:

1. A lamp base comprising a shallow cup-shaped shell having a substantially circular interior, the exterior of said shell being formed with flat parallel surfaces on opposite sides thereof for indexing the base in a socket, and means to locate a pair of spaced contacts on the bottom of said shell in a line bearing a predetermined relationship to the planes including said flat side surfaces. 10

2. A lamp base comprising a shallow cup-shaped shell having a substantially circular interior, the exterior of said shell being formed with flat parallel surfaces on opposite sides thereof for indexing the base in a socket, and means to locate a pair of spaced contacts on the bottom of said shell in a line bearing a predetermined relationship to the planes including said flat side surfaces and socket-engaging projections extending transversely from the said flat side surfaces. 20

3. A lamp base having a shallow, circular, lamp accommodating cavity, an external surface portion approximately square in transverse section and support engaging projections offset from said square surface portion and extending transversely in opposite directions from said base. 30

4. A lamp base having a shallow, circular, lamp accommodating cavity, an external surface portion approximately square in transverse section and support engaging projections offset from said square surface portion and extending transversely in opposite directions from said base, the bottom of said base having a plurality of current instead accommodating apertures aligned in a plane including the most widely spaced portions of said projections. 40

5. A lamp base having a shallow, circular, lamp accommodating cavity, an external surface portion approximately square in transverse section and support engaging flanges offset from said square surface portion in the direction of the mouth of said cavity and extending in opposite directions from said base. 45

6. A lamp base having a shallow, circular, lamp accommodating cavity, an external surface portion approximately square in transverse section and support engaging flanges offset from said square surface portion in the direction of the web of said base and extending in opposite directions from said base. 50

7. A lamp base having a shallow, circular, lamp accommodating cavity, an external surface portion approximately square in transverse section and support engaging flanges offset from said square surface portion, disposed in a common plane including the mouth of said cavity and extending in opposite directions from said base, said flanges having an arcuate edge extending through an angular distance of approximately 104 degrees measured from the center of said circular cavity. 60

8. In combination, a lamp comprising a base having an exterior surface portion approximately square in transverse section and outwardly projecting, planar flanges offset from said square base portion and a holder for said base having elastic means engaging said base and exerting force longitudinally thereof to retain the base in the holder, said holder also having an aper- 70

ture of approximately the same shape as the surface of said base including said flanges and of larger size than said surface so that the entire base may be passed therethrough for engagement with the elastic means of said holder. 5

9. In combination, a lamp comprising a base having an exterior surface portion approximately square in transverse section and outwardly projecting, planar flanges offset from said square base portion, the bottom of said base having exposed electrical contacts and a holder for said base having an aperture of approximately the same shape as the surface of said base including said flanges and of larger size than said surface so that the entire base may be passed therethrough for engagement with said holder, said holder also having resilient, base contact engaging contacts juxtaposed to said aperture for exerting a holding force longitudinally of said base. 10

10. In combination, a lamp comprising a base having an exterior surface portion approximately square in transverse section and outwardly projecting, planar flanges offset from said square base portion, the bottom of said base having exposed electrical contacts and a holder for said base having an aperture of approximately the same shape as the surface of said base including said flanges and of larger size than said surface so that the entire base may be passed therethrough for engagement with said holder, said holder also having resilient, base contact engaging contacts provided with grooves to prevent rotation of said base in said holder, said contacts being juxtaposed to said aperture and exerting a holding force longitudinally of said base. 20

11. In combination, a lamp comprising a base having an exterior surface portion approximately square in transverse section and outwardly projecting, planar flanges offset from said square base portion and a holder for said base having an aperture of approximately the same shape as the surface of said base including said flanges and of larger size than said surface so that the entire base may be passed therethrough for engagement with said holder, said holder also having spaced edge portions juxtaposed to said aperture and defining a slot accommodating and engaging the square portion of said base to prevent rotation of said base in said holder. 30

12. In combination, a lamp comprising a base having an exterior surface portion approximately square in transverse section and outwardly projecting, planar flanges offset from said square base portion and a holder for said base having an aperture of approximately the same shape as the surface of said base including said flanges and of larger size than said surface so that the entire base may be passed therethrough for engagement with said holder, said holder also having a square indentation juxtaposed to said aperture and accommodating and engaging the square portion of said base to prevent rotation of said base in said holder. 40

13. A holder for a lamp base comprising a cup-shaped shell having top and bottom surfaces of different configuration, said holder comprising a member of resilient sheet metal having opposite edge portions folded over its center portion and disposed in a common plane spaced from and parallel to the center portion with the adjacent edges slightly separated, said center portion having a base receiving aperture opposed to the space between said edges, said sheet metal member having also inwardly opening, shallow depressions conforming in shape and engageable with

one of the said surfaces of said base for indexing said base in said holder.

14. A holder for a lamp base comprising a cup-shaped shell having top and bottom surfaces of different configuration, said holder comprising a member of resilient sheet metal having opposite edge portions folded over its center portion and disposed in a common plane spaced from and parallel to the center portion with the adjacent edges slightly separated, said center portion having a base-receiving keyhole slot opposed to the space between said edges, said sheet metal member having also inwardly opening, shallow depressions at the sides of the smaller end of said keyhole slot and conforming in shape to and engageable with the top of said base for indexing said base in said holder.

15. A holder for a lamp base comprising a cup-shaped shell having top and bottom surfaces of different configuration, said holder comprising a member of resilient sheet metal having opposite edge portions folded over its center portion and

disposed in a common plane spaced from and parallel to the center portion with the adjacent edges slightly separated, said center portion having a base-receiving aperture opposed to the space between said edges, said sheet metal member having also inwardly opening, shallow depressions in said edges opposite said base-receiving aperture and conforming in shape to and engageable with the bottom of said base for indexing said base in said holder.
